UNITED STATES PATENT OFFICE.

CLEMENT MACE OWEN, OF WARRINGTON, ENGLAND.

LIMING AND OTHER TANNING OPERATIONS UPON HIDES OR SKINS.

1,342,866.

Specification of Letters Patent.

Patented June 8, 1920.

Application filed August 11, 1919. Serial No. 316,920.

To all whom it may concern:

Be it known that I, CLEMENT MACE OWEN, a subject of the King of England, residing at Stockton Heath, Warrington, in the 5 county of Lancaster, England, have invented new and useful Improvements in and Connected with Liming and other Tanning Operations Upon Hides or Skins, of which the following is a specification.

10 This invention has reference to the preliminary operation in the tanning of hides or skins of "liming"—in which they are operated upon by the known milk of lime liquor in pits or tanks for the primary purpose of

15 loosening the hair and swelling the hide or skin—and other similar operations; and it has primarily for its object and effect to render the action of the liquor upon the hides or skins more uniform and effective, 20 to reduce the time occupied in effecting the treatment, and diminish the labor and cost.

The hides or skins are suspended and held separate or apart in the liquor in the pits or tanks, and the liquor is kept in gentle movement, so that the lime, or other ingredient, 25 is kept in suspension in the liquor and distributed, and as the liquor which is acting on the surface of the hides or skins is absorbed by them, it is replenished with fresh 30 and more liquor, with the effects above referred to.

The means for producing vibratory or pulsatory or like movement of the liquid is illustrated in the accompanying drawings, 35 in which Figure 1 is an end elevation of a pit showing the vibratory or pulsatory means within it, while Fig. 2 is a longitudinal section, and Fig. 3 is a plan. Fig. 4 is a detail showing a modified arrangement of 40 vibratory device or means.

Referring to Figs. 1 to 3, the arrangement shown consists of a multiplicity of double paddles 1, disposed near the bottom of the tank, a number of which are mounted on a 45 plurality of shafts 2 extending across the pit at the bottom, supported in bearings 3 resting on frames 4, which are secured to the bottom of the pit.

All the shafts 2 are coupled together by a 50 coupling bar 5, connected by pin joints to arms 6 fixed on the shafts 2; the rod 5 extends along the center of the bottom of the pit, and is reciprocated by a vertical rod 7 extending down into the pit, and suitably

mechanically operated from above, it being 55 connected to the bar 5 by the bell crank 8. Thus by reciprocating the bar 7 the shafts 2 are rocked, and the paddles 1 vibrated. The amount of stroke of the paddles may be about that indicated by the dotted line in 60 Fig. 1.

The hides 10 in the case shown are placed in and lifted out of the pits, and suspended in them, on rods 11, placed across the top of the tank or pit, and supported suitably 65 by links or cords 12, which are secured along each side of the tank to pins or the like in any suitable way.

The paddles 1 are of duplex form, that is one blade is on each side of the axis of 70 their supporting shafts, and they are made preferably of the form shown in Fig. 3, namely, larger at the blade portions proper, and smaller at the inner arm and boss portions, which may be separate parts from the 75 blades, and the latter attached to them, as indicated by the drawings.

Directly above the shafts 2 there is a partition board 9, fixed in jaws or sockets formed on the upper part of the bearings 80 3; these serving as a species of guide or controlling means for the movement of the liquor on each side of the shaft; that is the two bodies of liquid acted upon by the paddles, on each side.

In the case shown in Fig. 4, only two sets of paddles are employed, in which case, the blades proper consist of bars extending between two arms fixed on the shafts 2. This form is more suitable for wide pits or tanks. 90

By vibrating the paddles through an arc such as described say 60° to 90° , the ingredients in the liquor will be kept in suspension and properly distributed in the liquor, and the required movement of the liquor is produced.

In the case where the invention is applied to liming, for the purpose of dehauling the hides or skins, the effect of the paddles and their movement is to keep the lime in suspension in the liquor, and they tend to draw the disturbed lime upward among the hides, which are suspended in the liquor.

The paddles and gear may in some cases be covered over by a wooden grate, just 100 above them, but generally, such a grating is not necessary.

With regard to the rate of movement of

the paddles, I find that when working with lime liquors in pits or tanks, about 50 strokes a minute is a suitable rate of movement.

What is claimed is:—

- 5 1. A tank vat for liming hides or skins, having a plurality of sets of paddles arranged in the lower portion thereof, the paddles of each set being alined, a shaft supporting the paddles of each set, means for 10 simultaneously and similarly operating all of said shafts to reciprocate the paddles, and means having a fixed relation to each shaft to direct the liquid disturbed by the paddles upwardly in the vat.
- 15 2. A tank vat for liming hides or skins,

having a series of shafts mounted in the bottoms thereof, a plurality of paddles mounted on each shaft, means connecting all of said shafts to simultaneously and similarly reciprocate all of said paddles, and partitions 20 arranged above and in line with the respective shafts to direct the liquid disturbed by the paddles in the upward direction.

In testimony whereof I have signed my name to this specification in the presence of 25 two subscribing witnesses.

CLEMENT MACE OWEN.

Witnesses:

SOMMERVILLE GOODALL,

ALICE PERKINS.
